DESIGN FOR A SUPPORT FOR PLAYING CARDS

Cecil B. Woofter, St. Paul, Minn., assignor to Brown & Bigelow, St. Paul, Minn., a corporation of Minnesota

Application May 17, 1945, Serial No. 119,587

Term of patent 14 years

(Cl. D34—13)

To all whom it may concern:

Be it known that I, Cecil B. Woofter, a citizen of the United States, residing in Saint Paul, county of Ramsey and State of Minnesota, have invented a new, original, and ornamental Design for a Support for Playing Cards, of which the following is a specification, reference being had to the accompanying drawing, forming part thereof.

I claim:

The ornamental design for a support for playing cards, as shown.

CECIL B. WOOFTER.
